UNITED STATES PATENT OFFICE.

FRANCIS E. McVAY, OF PAWTUCKET, RHODE ISLAND.

DRAFT-CONTROL DEVICE.

Application filed February 20, 1926. Serial No. 89,754.

This invention relates to draft control devices and more particularly to draft controls for steam or hot water household furnaces.

5 An important object of the invention is to provide a device of this character which is automatic in its operation and which may be very readily and cheaply applied to the furnace.

10 A further object of the invention is to provide a device of this character whereby a proper relation is maintained between the drafts at all times, thus preventing over-checking or under-checking of the fire in response to an increase in pressure or temperature within the furnace.

15 A further and more specific object of the invention is to provide a device of this character which will permit the draft to be removed from the furnace without fully checking the furnace and will permit the furnace to be partially checked by the ordinary flue damper without checking the same at the coal check or door openings of the furnace.

20 A further object of the invention is to provide a device of this character which may be readily adjusted to suit the needs of the particular furnace to which it is applied.

25 These and other objects I attain by the construction shown in the accompanying drawings, wherein for the purpose of illustration is shown a preferred embodiment of my invention and wherein:—

30 Figure 1 is a side elevation of a furnace provided with controls arranged in accordance with my invention;

35 Figure 2 is an enlarged detail view of the rear end of the arm showing the connections to the smoke pipe check;

40 Figure 3 is a section on the line 3—3 of Figure 2;

45 Figure 4 is a detail front elevation of the door showing the connections employed for the slide controlling the door check;

50 Figure 5 is a section on the line 5—5 of Figure 4;

55 Figure 6 is a detail side elevation of the upper portion of the furnace showing how the spring 29 removes the slack from the connections with the door check.

60 Referring now more particularly to the drawings, the numeral 10 generally designates a furnace having the usual under draft 11, flue check 12 and fire door check 13. The flue check 12 is biased, as by a counter-

weight 14 to normally maintain the same in closed or operative position while the fire door check 13 is biased, as by a spring 15 to normally maintain the same in inoperative position in which a slide 16 closes the openings 17 of the fire door.

65 In accordance with my invention, I provide a lever 18 suitably pivoted, as at 19, upon the furnace and having connections 20, 21, 22 with the under draft 11, flue check 12 and fire door check 13. These connections are such that the draft 11 may be closed slightly before the flue check 12 assumes its closed position and both the draft 70 11 and flue check 12 may be fully closed before the fire door check 13 is effected. The connection between the lever 18 and the draft 11 is in the form of a link pivotally connected to the draft door 23 and to the 75 lever 18 at the end thereof adjacent the flue check 12, this link being formed in two slidably connected sections 24 and 25.

80 The connection 21 between the flue check 12 and the lever 18 is in the form of a flexible element, such as a chain which permits a predetermined elevation of the adjacent end of the lever before any movement of the flue check is effected. In the present instance, this connection is shown as tightening 85 when the lever 18 is horizontally disposed and is exercising a pull to open the check 12 as the adjacent end of the lever moves upwardly from its horizontal position.

90 The connection 22 between the lever and the fire door check 13 is connected with the lever at the opposite side of the pivot 19 from the connections 20 and 21. This connection includes a bell crank lever 26 pivoted to the fire door and having one arm thereof connected with the slide 16, as at 27. The opposite arm is connected with the lever 18 by a chain 28 of such length that the chain becomes taut as the lever arrives 100 at that position in which the flue check 12 is fully closed. In order to prevent slack in the chain from becoming looped about the end of the lever 26, when the end of the lever to which the connection is made is depressed, 105 a light spring 29 is connected between spaced links of the chain so that this slack is taken up. This spring, as the lever shifts, will extend to permit the chain to tighten so that operation of the slide 16 may be effected. 110 The lever 18 is engaged at that side of the pivot to which the connection 22 is made

2

by an expansion device 30 which may be either a pressure responsive device if the furnace is employed with steam or a thermostatic element if hot water is employed. 50

5 This end of the lever is also provided with an adjustable counterweight 31 for regulating the pressure or temperature at which the lever is shifted by the expansion element 30.

10 In the operation of the device, if the temperature or pressure rises, the expansion element 30 will elevate the forward end of the lever 18 with the result that the draft door 23 is closed and the damper or flue check 12 55 partially closed. If the temperature continues to rise, the damper 12 continues to move to its closed position and finally arrives at this closed position. If this fails to check the rise, continued operation of the 20 lever will cause the slide 16 to be moved to its open position with the result that the fire door check 13 is brought into operation.

It will, of course, be understood that the construction hereinbefore set forth is obviously capable of a certain range of change and modification without materially departing from the spirit of the invention and I accordingly do not limit myself to such specific structure except as hereinafter claimed.

25 30 I claim:—

1. In combination with a furnace including the usual under draft, a flue check biased to maintain the same in closed position and a fire door check having the usual slide, the 35 slide being biased to maintain the same in closed position, a pivoted lever and connections between said lever and the under draft, flue check and fire door check whereby continued movement of the lever in one direction 40 consecutively closes the under draft, operates the flue check and opens the slide of the fire door check.

2. In combination with a furnace including the usual under draft, a flue check biased 45 to maintain the same in closed position and a fire door check having the usual slide, the

slide being biased to maintain the same in closed position, a pivoted lever, connections between said lever and the under draft, flue check and fire door check whereby continued 55 movement of the lever in one direction consecutively closes the under draft, operates the flue check and opens the slide of the fire door check and an expansion element 60 operated from the furnace for moving the lever in said direction.

3. In combination with a furnace including the usual under draft, a flue check biased to maintain the same in closed position and a fire door check having the usual slide, the 65 slide being biased to maintain the same in closed position, a pivoted lever, and connections between said lever and the under draft, flue check and fire door check whereby continued 70 movement of the lever in one direction consecutively closes the under draft, operates the flue check and opens the slide of the fire door check, the movement of the lever in the opposite direction permitting the fire door check to be completely closed under the influence of its bias before the flue check is shifted.

4. In combination with a furnace including the usual under draft, a flue check biased to maintain the same in closed position and a fire door check having the usual slide, the 75 slide being biased to maintain the same in closed position, a pivoted lever, and connections between said lever and the under draft, flue check and fire door check whereby continued movement of the lever in one direction 80 consecutively closes the under draft, operates the flue check and opens the slide of the fire door check, the movement of the lever in the opposite direction permitting the fire door check to be completely closed under the influence of its bias before the flue check is shifted and partially opening said flue check before the under draft is opened.

In testimony whereof I hereunto affix my 85 signature.

FRANCIS E. McVAY.
